UNITED STATES PATENT OFFICE

2,179,069

SELVAGE FORMING DEVICE

Woodruff T. Sullivan, Norwich, Conn.

Original application October 14, 1938, Serial No. 235,044. Divided and this application March 29, 1939, Serial No. 264,854

10 Claims. (Cl. 139—127)

This invention relates to a selvage forming device, which is shown and described in my original application, filed October 14, 1938, Serial No. 235,044, entitled "Shuttleless loom", and this case disclosure is a division from said application, Serial No. 235,044, which became U. S. Patent No. 2,170,770.

An object of this invention is the provision of simple and efficient means for turning the cut end of the filling back into the shed.

Another object of the invention is the construction of a novel and efficient selvage forming device that works in timed relation with the means for drawing the weft or filling across the shed and cutting said filling, whereupon the selvage forming device takes or receives the cut end of said filling and efficiently places same in the edge of the fabric or shed.

A still further object of the invention is the construction of a selvage or looper device with an efficient jaw device, which jaw device is capable of efficiently holding the cut end of a filling while it is being placed in the shed, whereby a very durable and efficient selvage is formed upon the fabric.

With the foregoing and other objects in view, the invention comprises certain novel constructions, combinations and arrangements of parts as will be hereinafter fully described, illustrated in the accompanying drawings, and more particularly pointed out in the appended claims.

In the drawings:

Figure 1 is an enlarged fragmentary view of the loom, showing particularly in plan view the selvage forming or looper device, while

Figure 2 is an edge view of the same.

Figure 3 is a fragmentary view of the shuttleless loom, showing in top plan the shed, the selvage forming or looper device, one of the retrieving devices, etc.

Figure 4 is an enlarged plan view of the looper jaws, while

Figure 5 is an outer end view of the same.

Figure 5A is an enlarged fragmentary view of the outer end of the jaws of the looper.

Figure 5B is an enlarged elevated view of the outer end of the jaws of the looper.

Figure 6 is a sectional view taken on line 6—6, Fig. 5A, and looking in the direction of the arrows.

Figure 7 is a diagram, showing the first position of the looper, in operation; Figure 8 is the second position; Figure 9 is the third position ("beat up"); Figure 10 is the fourth position ("start of looping operation"), and Figure 11 is

the fifth position, showing looping operation complete.

Referring to the drawings, in which I have shown the preferred embodiment of this invention, I designate a bearing block which is fastened to a suitable part of a loom frame by means of bolts 2. A movable shaft 3 passes through a slotted portion 4 of the bearing block 1, this shaft is provided on its rear end with a collar 5 (Fig. 1). The shaft 3 is provided with a pin 6 which rides in slot 7 formed in said bearing unit of portion 4. The shaft 3 is also provided with a collar 8 on its forward end, which collar 8 acts as a stop for said shaft 3. On shaft 3 is also mounted a hub shaped piece 9. The under side 10 of hub shaped piece 9 is provided with a downwardly extending portion 10 (see dotted line, Fig. 2). Portion 9 is also provided with projection 11; this projection 11 and portion 9 constitutes a bracket, upon the rear end of which is rotatably mounted an arm 12. This arm 12 is fixedly secured to pin 13. Beside pinion 14 and fixedly secured thereto is said arm 12. Mounted securely on the end of arm 12 and extending therefrom is the holder 15. At the lower end of holder 15 is mounted the curved filling looper device 16. Slidably mounted on shaft 3 is sleeve 17. At the lower end of sleeve 17 is secured collar 18. Collar 18 has an extended portion 22, the purpose of which is to provide a portion of collar 18 which may be acted upon by lever 20 (Fig. 1), to impart motion thereto. Mounted on shaft 3 and sleeve 17 is coil spring 21. The function of spring 21 is to keep 9 and 18 in the position shown in the drawings, until the extended portion 22 is acted upon by lever 20. Mounted on shaft 3 between the bearing faces of portions 4 and 9 is coil spring 23. The function of said spring 23 is to keep these units in an extended position, so that shaft 3 is extended to the position shown in the drawings, with collar 8 acting as a stop. Spring 23 must be considerably stronger than spring 21. Extending from the bearing block 1 are two lugs 24 (Fig. 1), which form bearings for pin 25. On this pin 25 is mounted the hub 26, which has the extended portion 27. The part of extended portion 27 has the hook 28 (Fig. 2), which hook 28 is on the upper side of the end of the outwardly extending arm 29 (Fig. 1). The center of the hooked portion 28 is in line with the center line of the hub 9 on the bottom of which is the pointed portion 30. Hooked portion 28 has a rearwardly extending finger 31. The function of finger 31 is to prevent contact between the hook 28 and the spring 23. A lever 32

is provided at one end with a cam unit 33. Fas-
tened to the lay structure is the arm or lever
20. On the under side of extended portion or
lever 32 is mounted a flat spring 34 which is
5 fastened by means of screw 35. The purpose of
this spring 34 is to keep said lever 32 in proper
position. As the lay structure, which carries
20 moves to a more forward position, lever 20
makes contact with collar 18 at 22 (Fig. 1) of
10 the looping mechanism. This carries the hub 18
on sleeve 17 forward, against the slight tension
of spring 21 until it is stopped from further mo-
tion on shaft 3, as the face of hub 9 contacts
15 the end of the face of sleeve 17. Shaft 3 has re-
mained stationary as it is held in position by the
relatively strong spring 23, acting between the
collar or hub 9 and the face of the bearing 1.
As hub 18 has moved and with it extension 19,
20 this movement has caused pinion segment 14
to rotate by the effort of the rack teeth in mesh
with the pinion teeth. As this rotation takes
25 place, the filling 36 is still under tension and lo-
cated in the looper 16, and the filling in effect
slides around into the end of the device 16 where
it is held from falling out by means of the
30 pronged construction 37, on the tube or jaws
38 of said device 16. Note that at this point the
selvage forming or looper device is now outside
the warp line and clear of same. Also, that this
35 rotation has been relatively rapid in operation,
due to the pinion and rack arrangement. This
allows the looper device 16 to move out of po-
sition so that the reed does not come in contact
with the looper device before it has cleared it-
30 self. Figure 1 shows the looper device in its
normal position. Figures 3 shows the looper de-
vice in the warp, just before rotation. Now as
the lever 20 moves further forward, it carries
40 with it hub 18. Inasmuch as hub 18 is mounted
on sleeve 17, the spring 21 has been contracted
and there can be no further action of said spring
because sleeve 17 is against hub 9, hub 9 is com-
45 pelled to take any further movement, which it
may, by causing shaft 3 to slide in its bearing
portion 4 of bearing block 1. This move-
ment causes spring 23 to be contracted. Cam
surface 39 (dotted line, Fig. 2) on projection 40
of the lever 20 (to which lever 20 projection 40
is secured) acts upon the cam surface of lever
50 32, causing the latter to be forced in a downward
direction, thus assisting hooked portion 28 to
escape the locking point, at 30, on the hub 9.
At such time, when there has been sufficient
55 movement to cause the cam shaped surfaces 39
and 33 to become disengaged, it will be noted that
locking point 30 of lever 32 prevents said lever
from rotating in an upward direction by action
of spring 34, because it contacts and slides along
60 the lever. This condition prevents any interfer-
ence between the hooked portion 28 and any
other part of the mechanism with which it might
otherwise interfere.

During the latter part of the motion, the filling
65 36 has moved up to a position near the apex
(or fell) of the warp threads, and it has also
been cut by the cutting device at each end, thus
releasing it from the carrier or retrieving device
jaws and allowing the jaws to move to a more
70 forward position than that assumed by the reed
when in the beat up position. This is necessary
because the center line of the operating tube
and inserting or retrieving devices (see illustrat-
ing diagram in Fig. 3) is slightly in advance of
75 the front face of the reed, which is a necessary
condition to allow the jaws to operate (open and

close) at the time of transfer of filling thread
near the center of the weave without damage to
the reed through contact therewith.

Now, as the lay reverses its movement suffi-
ciently and carries the lever 20, the hook 28 5
engages the downwardly extending portion of hub
9. This prevents the device from moving as a
unit any further. Note that the cam surfaces
39 and 28 have not yet contacted each other.
The idea of this movement is to allow the looper 10
to be moved up to a position where it may be
turned into the shed, and also allow time for
the shed to open sufficiently to allow clearance
therein for the looper to enter. Of course, the
shed is closed after the loose end of the filling 15
36 has been turned in with the next pick.

The mechanism is now in position to execute
the looping or selvage forming operation and
that is accomplished in the following manner.
It will be noted that the pick, the ends of which 20
are now in the jaws 38 of the looper device 16,
has been bound in, as the warp threads have
changed since its insertion and it has been beaten
up by the reed in the lay. This means that when
the looper device operates, it will be inserting the
25 ends of mentioned pick in the shed opening
formed to receive the succeeding pick. In other
words, the ends are not turned into the opening
of the same pick, but into the opening existing
for the subsequent pick. 30

As lever 20 moves further, it allows hub 9 on
sleeve 17 to move with it, due to the action of
spring 21. This movement takes place because
the hooked condition of hook 28 prevents the
unit from moving as a whole, as hub 18 moves 35
with sleeve 17 away from hub 9, through the
effort of spring 21 on shaft 3. This causes ro-
tation of the pinion 14 in an opposite direction
from its previous rotation, causing the looper
40 device 16 to rotate back into the position shown
in Figure 1. During this motion, it has carried
the free end of the filling 36 into a position
between the warp threads.

It will be noted that cam shaped surface 39
in connection with the cam face of unit 33 45
have contacted and acted to particularly disen-
gage hook 28 and slightly more movement will
allow this hook 28 to become totally disengaged
and thus allow the mechanism to move further
as a whole unit to its initial position, as shown 50
in Figure 1, during which forward movement it
will have released any short end of filling re-
mainning in the looper jaws 38 and 38a, and will
then be in position to receive the next pick and
repeat the cycle as hereinbefore explained for 55
the next pick.

It is to be understood that the looping as well
as the cutting operations are performed at both
sides of the weave by similar devices as herein-
before described for the operation, opposite hand 60
units being necessarily used.

Referring to Figures 4 to 6, the curved looper
jaws 38 and 38a are integrally connected at their
inner ends 40. The prong construction 37 is
65 formed at the outer ends of the jaws 38 and 38a,
to grip the filling 36 sufficiently to hold it
while the end is being turned back into the shed.
The jaws 38 and 38a extend longitudinally of
the right angled extension 15a, of the holder 15.
The extreme outer end 38b of jaw 38 is curved 70
to the outer end of the looper (Fig. 5A), while
jaw 38a is curved only to point 38c which is short
of the outer end of 38b; the curvature 38c ter-
minates in an outwardly extending fin 38d, by
which the filling passes, during the operation. 75

These efficient and novel elements, of the looper produce a highly efficient holding means for the filling 36, during the operation of the looper which will now be described.

5 Figure 7 depicts the looper 16 in its initial position. The lay and reed is advancing toward the front of the loom and the filling 36 has been inserted and the jaws have brought it to a position as shown in the bell-shaped central portion 10 of the looper 16. The looper 16 is now ready to commence its first operation. As the lay now advances, due to contact of lever 22 with a portion 15 of the looper arrangement at 22, rack 19 operates pinion 14 and causes looper 16 to rotate to the position shown in Figure 8. This action has taken place while the spring 21 has been contracted and continues until sleeve 17 is stopped by contacting the face of hub 9. The only portions of the device that have moved are 20 the looper rack and pinion and the sleeve on rod 3. It will be noticed that this rotation of the looper has caused the filling to change its position in the looper by sliding around in the open part of said looper from a position shown 25 at B, Fig. 7, to the position shown at C in Fig. 8. The reed has moved approximately one-half inch to accomplish this result.

Now any further movement of the lay toward the front causes the looping device to move as 30 a whole and slide in its bearing 4 until the most forward position of the lay has been reached as shown in Figure 9, which is the beat up position. Just before this position has been reached, the scissors 43 have operated to free the filling from 35 the jaws and the jaws are then opened to release the cut end remaining in the retrieving device. Previous to cutting, however, the inserting device has closed to grasp the filling preparatory to the next filling inserting operation. Note how 40 the filling has been pulled through the end of the looper somewhat because the looper has passed from inside of the warp apex to outside of the same. This leaves a much smaller end in the looper to be freed after the looping has been done. It is also to be noted that from the position shown 45 in Figure 8 to the position shown in Figure 9, which is while the warp shed is closing down upon the inserted filling, the jaws are slightly ahead of the point C of the looper so that the tendency is to retain the filling in the looper until the same has been securely held by the 50 change of the warp threads in the weave.

The lay has now reached its most front position and it now reverses and moves toward the rear. This motion continues to take place until the position as shown in Figure 10 is reached. During this movement, the looper has advanced toward the rear of the loom approximately seven-eighths of an inch and away from the 55 beat up position. This movement has allowed the shed to open up substantially so that there will be sufficient room for the looper to enter same. When this position has been reached, the hook 28 locks on the collar 9 and prevents further motion of the looper as a unit. This is the position at which the looper is ready to reverse its rotation and insert the end of the filling into the shed in the place where the succeeding pick will be inserted.

60 Any further movement of the lay will allow the spring 21 (which is contracted) to expand, and, consequently, perform the looping operation through the action of the rack and pinion arrangement. That is, the pinion at A, Fig. 7, 65 has rotated anti-clockwise and taken with it the

looper to the position shown in Figure 11. It is to be noticed that when the reed is in the beat up position, it is further toward the front of the loom than the corresponding point (the fell) in the weave when the reed is away from this front position. This can be explained by the fact that the weave has a tendency to move toward the back of the loom after it is pounded up and the reed has left it; I have shown this in Figure 10, at D, as cloth expansion. It is to be 10 understood that while motion of the reed has taken place between the positions shown in Figures 10 and 11 the pinion at A, Fig. 7, has not moved; it has simply rotated as hereinbefore explained. The same condition exists between the 15 positions shown in Figures 7 and 8. The looping operation has now been completed except that the looping device has not yet resumed its initial position.

As further lay motion takes place, hooked condition of 30 and 28 is caused to be released by the action of contact between the cam surfaces of the lever 20 on the lay at the portion 40 and the portion of lever 27 at 33. This action releases the locked condition and allows spring 23 to expand, causing the device to assume its initial position against the stop 8 to the position as shown in Figure 7. There will be no filling in the shed at this time, however, as the next pick has not yet been inserted.

30 In Figure 3, 41 designates the lay sword to which is secured, by any suitable means, lever 20. 42 designates one of the retrieving devices, which is holding the filling 36. The filling cutting means is shown at 43. This Figure 3 illustrates the position of the cooperating means, in a shuttleless loom, for causing the selvage forming function of said loom. For a more specific disclosure and full description of units 42, 43, etc., reference should be had to my U. S. Patent 40 No. 2,170,770 granted Aug. 22, 1939.

35 It is also to be understood that the curved or semi-circular structure of the looper jaw-unit 38, with its peculiar opening, is very important, because it is exposed to the filling as the filling advances toward the looper, giving it the advantage of being automatic, so to speak, of locating the filling in the looper before rotation takes place.

45 While I have described the preferred embodiment of my invention and have illustrated same in the accompanying drawings, certain changes or alterations may appear to one skilled in the art to which this invention relates during the extensive manufacture of same and I, therefore, 50 reserve the right to make such changes or alterations as shall fairly fall within the scope of the appended claims.

55 What I claim is:

60 1. In a shuttleless loom, the combination with a support, of an extended portion and means supporting said extended portion upon said support, a pinion carried by said extended portion, an arm on said extended portion and fixedly connected to said pinion, a rack unit meshing with said pinion, means for operating said rack unit, looper jaws fixedly secured to said arm, said jaws provided at their outer ends with filling engaging prongs, and means for delivering a filling to said jaws.

65 2. In a selvage forming device, the combination with a support, of a spring pressed shaft on said support, bracket means yieldably supported upon said shaft, a jaw device provided with a pinion rotatably mounted upon said bracket means, a 70

- rack unit yieldably mounted on said shaft and engaging said pinion, and means adapted to engage said rack unit causing movement thereof upon said shaft and rotation of said pinion for actuating said jaw device.
3. In a selvage forming device, the combination with a support, of a filling looper device, means movably mounting said looper device upon said support, said filling looper device comprising a unit including a pair of elongated jaws, said jaws provided near their outer end with pronged means, means for moving said filling looper device upon said support, and means delivering a filling to said jaws.
- 15 4. In a selvage forming device, the combination with a support, of a filling looper device, means movably mounting said looper device upon said support, said filling looper device comprising a shaft-like unit, jaws extending longitudinally of a part of said shaft-like unit, said jaws provided with filling holding means on their inner faces, means for moving said looper device upon said support, and means delivering a filling to said jaws.
- 25 5. In a selvage forming device, the combination with a support, of a filling looper device, means movably mounting said looper device upon said support, said filling looper device comprising a shaft-like unit, elongated jaws on said shaft-like unit and being integrally connected at their inner ends with their outer ends being capable of lateral movement, said outer ends provided with filling holding means, means for moving said looper device upon said support, and means 30 delivering a filling to said jaws.
- 35 6. In a selvage forming device, the combination with a support, of a filling looper device, means movably mounting said looper device upon said support, said filling looper device comprising a shaft-like unit, elongated jaws on said shaft-like unit and being integrally connected at their inner ends with their outer ends extending downwardly, said jaws provided near the downwardly extending ends with a pair of holding prongs, 40 means for moving said looper device upon said support, and means delivering a filling to said jaws.
- 45
7. In a selvage forming device, the combination with a support, of a filling looper device movably mounted on said support, said looper device comprising a pair of jaws, one of said jaws being gradually curved inwardly at its outer end and the other jaw curving inwardly to a point short of the outer end of the first-mentioned jaw, said last-mentioned jaw provided with a fin at its outer end extending to the outer end of said looper device, and means for operating said looper device.
8. In a selvage forming device, the combination with a support, of a looper device, means mounting said looper device on said support, said looper device comprising a pair of jaws, said jaws curved at their outer ends towards each other, said jaws provided at their outer ends with a filling-receiving space, for holding a filling during part of the operation of said looper device, means delivering a filling to said jaws, and means for moving said looper device upon said support.
- 15 9. In a selvage forming device, the combination with a support, of a looper device, means mounting said looper device upon said support, said looper device comprising a pair of longitudinally curved jaws, said jaws being curved transversely towards each other, said jaws provided with means for holding a filling therebetween, means delivering a filling to said jaws, 20 and means for moving said looper device upon said jaws.
- 25 10. In a selvage forming device, the combination with a support, of a looper device mounted on said support, said looper device comprising a jaw curved inwardly throughout the length of its outer end, a second jaw curved partly at its outer end toward the first-mentioned jaw and terminating in a filling-engaging fin at the outer end of said looper device, means delivering a filling to said jaws, and means for moving said looper device upon said support, substantially as shown and described.
